UNITED STATES PATENT OFFICE.

RALPH BERT PARTRIDGE, OF BIRMINGHAM, ENGLAND, ASSIGNOR TO SOUTHALL & SMITH LIMITED, OF BIRMINGHAM, ENGLAND.

FILLING DEVICE.

1,427,013.

Specification of Letters Patent. Patented Aug. 22, 1922.

Application filed August 9, 1921. Serial No. 490,979.

To all whom it may concern:

Be it known that I, RALPH BERT PARTRIDGE, a subject of the King of Great Britain and Ireland, residing in the city of Birmingham, England, have invented certain new and useful Improvements Relating to Filling Devices, of which the following is a specification.

This invention relates to machines for packing or measuring powdered materials, of the type in which a receptacle placed over the outer (and usually the lower) end of a delivery nozzle is charged with material by means of a rotating screw or worm situated within the nozzle. Ordinarily the outer end of the nozzle is quite open, and it is found that the material is liable to clog at that end, resulting in retardation of the speed of action of the machine, and inaccuracies in the amounts of the material delivered in successive operations.

The present invention has for its object to obviate the above mentioned defect in a simple and reliable manner, and for this purpose the invention comprises the use at the delivery end of the charging nozzle, of a grid, through which the material passes before entering the receptacle placed over the nozzle.

In the accompanying sheet of explanatory drawing:

Figure 1 is a part sectional side elevation and Figure 2 a sectional plan showing diagrammatically one mode of carrying the invention into effect.

The grid *a* aforesaid is constructed in the form of a number of narrow strips radiating from a common centre. This grid is placed within the outer end of the nozzle *b*, the ends 40 of the strips terminating at the inner cylindrical surface of the nozzle. The strips may each be sharpened to a knife edge as shown at the upper side of the grid. Though a grid of this form is preferred, the invention 45 is not limited thereto.

Interiorly the nozzle is provided with the usual worm *c* by which the material fed into the upper side of the nozzle is forced out at

its lower end. Over the lower end of the nozzle is placed a receptacle as *d* to be charged, this receptacle being supported on a carrier *e* to which upward pressure is applied during the charging operation in any usual manner. While the material is being fed into the receptacle, the pressure exerted on the material by the worm forces the receptacle and its support downwards against the upward force applied to the support until the charging operation is completed, when the receptacle is withdrawn and replaced by another.

By means of a grid as above described, clogging of the nozzle is avoided, a free and uniform passage of material is ensured, and the amount of material delivered at each operation of the machine can be more accurately determined than when a plain open nozzle is used. The tendency found with the ordinary nozzle for the material to be extruded between the outer side of the nozzle and the open end of the receptacle which fits over the nozzle is eliminated, and further the grid serves to minimize the falling away from the nozzle of loose material after the motion of the worm has been stopped.

Having thus described my invention what I claim as new and desire to secure by Letters Patent is:

1. In machines of the type specified for packing or measuring powdered material into receptacles, the combination with a delivery nozzle, of a grid through which the material passes before leaving the nozzle, substantially as described.

2. In machines of the type specified for packing or measuring powdered material into receptacles, the combination with the outer end of a delivery nozzle, of a plurality of narrow strips radiating from a common centre and forming a grid through which the material passes before leaving the nozzle, substantially as described.

In testimony whereof I have signed my name to this specification.

RALPH BERT PARTRIDGE.
